(57) **CLAIM**

The ornamental design for a cosmetic skin treatment apparatus, as shown and described.

DESCRIPTION

FIG. 1 is a front, left side, and top perspective view of a cosmetic skin treatment apparatus according to the novel design.

FIG. 2 is a rear, right, and bottom perspective view of a cosmetic skin treatment apparatus according to the novel design.

FIG. 3 is a front view of a cosmetic skin treatment apparatus according to the novel design.

FIG. 4 is a right side view of a cosmetic skin treatment apparatus according to the novel design.

FIG. 5 is a left side view of a cosmetic skin treatment apparatus according to the novel design.

FIG. 6 is a top view of a cosmetic skin treatment apparatus according to the novel design; and,

FIG. 7 is a bottom view of a cosmetic skin treatment apparatus according to the novel design.

The broken line showing of the handle is included for the purpose of illustrating portions of the article and forms no part of the claimed design.
